UNITED STATES PATENT OFFICE

HARVEY J. VASCONCELLES, OF JACKSONVILLE, ILLINOIS

STOP SIGNAL

Application filed November 15, 1929. Serial No. 407,422.

This invention aims to provide a means whereby the motor-driving public will be trained and admonished to proceed with caution in driving an automobile across a railroad track.

Figure 1 is a plan, Figure 2 is a fragmental vertical section taken crosswise of the highway, and Figure 3 is a vertical section taken lengthwise of the highway, parts being broken away in Figures 2 and 3.

In the highway 1 leading to a railroad track 2, there is placed a passable obstruction, such as a rib 3, there being short upright posts 4 at the ends of the rib, the inner surfaces of the posts being convexed, as at 5, to deflect the wheels of a vehicle onto the rib 3 and not off it. The posts 4 carry standards 6 provided with signs 7 including a stop warning 8 and a legend 9 that indicates how many tracks there are to be crossed at the railroad 2.

The rib 3 may be painted a conspicuous color, and may be marked "Stop rise", as shown at 10, in as large letters as desired. The rib 3 is far enough from the track 2 so that the operator will have a chance to bring his car to a stop after running over the rib 3 and before encountering the track 2. Some distance back from the rib 3, perhaps about four hundred feet from it, there is a sign 11 on a post 12 by the side of the highway 1, the sign being marked as indicated at 14, to indicate that both a railroad and a stop rise or rib 3 are ahead, the distance to the railroad track being stated.

A car driver noticing the sign 11 will slow down, but if he does not slow down, the rib 3 will give his car a bump which will admonish him that the railroad is ahead, and he will have opportunity to apply his brakes. The sign 7 will show him that he is expected to stop, and will post him as to how many tracks he has to cross.

By means of the device claimed, the public will be instructed, after a short period of use, to approach a railroad carefully.

A preferred form has been shown and described, but I can make others, within the scope of what is claimed, and still keep within the spirit of my invention.

The highway 1 is broadened as at 10, the rib 3 and the posts 4 being located at the broadened portion 10 of the highway and where the highway is of maximum width. Because the highway is broadened, as at 10', 55 the posts 4 are spaced laterally from the line of travel and are out of the way, the posts, nevertheless being in full view of the drivers of approaching vehicles. The broadening of the highway, as at 10, tends to emphasize 60 and call attention to the posts 4 and the signs 7 thereon.

I claim:

In a device of the class described, a railway and a highway leading to the railway, the highway being open for traffic along its longitudinal center, the highway having a passable obstruction, in the form of a transverse rib, extended entirely across the highway and constituting means for admonishing a vehicle driver on the highway as to the proximity of the railroad track, combined signal and wheel-deflecting posts joined to the ends of the rib and to the highway, the highway being broadened, the rib extending unbrokenly between the posts, the rib and the posts being located at the broadened portion of the highway and where the highway is of maximum width, the inner surfaces of the posts being convexed to deflect the wheels of the vehicle toward the longitudinal center of the highway at the ends of the rib. 75

In testimony that I claim the foregoing as my own, I have hereto affixed my signature.
